UNITED STATES PATENT OFFICE.

FRANK H. HARRIMAN, OF HARTFORD, CONNECTICUT.

ELECTRICALLY-OPERATED RAILWAY-TRACK SWITCH.

SPECIFICATION forming part of Letters Patent No. 554,868, dated February 18, 1896.

Application filed December 11, 1895. Serial No. 571,803. (No model.)

To all whom it may concern:

Be it known that I, FRANK H. HARRIMAN, a citizen of the United States of America, residing at Hartford, in the county of Hartford 5 and State of Connecticut, have invented a certain new and useful Improvement in Electrically-Operated Railway-Track Switches, of which the following is a description, reference being had to the accompanying drawings, 10 wherein—

Figure 1 is a side elevation view of car, track, &c. Fig. 2 is a detail view, on an enlarged scale, a side view of the end of the trolley-pole and appurtenant parts as the trolley-wheel 15 approaches the point or place where the line-wire contacts are made. Fig. 3 is a top view of the parts shown in Fig. 2 with the weather-cover removed. Fig. 4 is a detail face view of the pinion and gear-sector intermediate 20 between the crank-handle, operated by the motorman, and the base of the trolley-pole. It shows a shaft cut in cross-section. The plane of that section is denoted by the dotted line $\alpha\alpha$ of Fig. 1. Fig. 5 is a top view of the 25 principal operating parts shown in Fig. 4. Fig. 6 is a top view of the electric-motor device whose operation effects the shifting of the switch of the railway-track. This view shows principally the electric switch on the top of 30 such motor. Fig. 7 is a view in vertical cross-section of the tongue of the switch, of the railway-track, and of the box which contains the electric motor already referred to, with 35 what is practically a side elevational view of the motor itself inside such box.

The object of the improvement is the production of a device, mechanism, or apparatus for use upon, or in connection with, a street-railway of the trolley variety, by means of 40 which the motorman upon the car can readily operate a track-switch he is approaching, utilizing, as a medium, electricity supplied by the line-wire of the trolley system.

In the accompanying drawings the mechanism is shown as in adjustment or position for shifting the track-switch, which the motorman is approaching, to the left.

The letter a denotes the car as a whole advancing in the direction indicated by the arrow thereupon.

The letter b denotes a crank-arm in front

of the motorman attached to shaft b' journaled on the top of the car. The motorman shifts this crank-arm to right or left, rotarily, accordingly as he desires to operate a track-switch which he is approaching to right or left. As the mechanism is shown in the drawings he shifts this crank-arm to his right in order to throw the track-switch to the left, but, of course, matters can be so adjusted 55 that shifting this crank-arm to the right also shifts the track-switch to the right.

The shaft b' is connected by a universal joint b^2 to the shaft b^3 in order that shafts b' and b^3 may have similar and synchronous 60 rotary motion. The shaft b^3 carries rigid thereupon the crank-arm b^4 , which is slotted from end to end, as indicated by dotted lines in Figs. 4 and 5. Whatever rotary motion is given to crank-arm b^4 , by moving crank-arm b , is communicated to gear-sector c through the medium of gear-sector shaft c' , crank-arm c^2 and crank-pin c^3 entering the said slot or mortise in crank-arm b^4 . This engagement of crank-arm c^2 with crank-arm 65 b^4 , through the medium of crank-pin c^3 entering the said slot or mortise, made lengthwise of the crank-arm b^4 , allows a similar engagement of parts on the other side of the pivot of the trolley-pole when the trolley-pole 70 is shifted, as nowadays is necessary in practice, to the opposite position from that shown in Fig. 1.

The gear-sector c meshes into and operates the pinion c^4 , and this, through the medium 75 of the flexible shaft d , communicates its rotary motion to the shaft d' , which is journaled upon and supported by the trolley-pole d^2 . The shaft d' carries at its upper end the rigid contact-finger d^3 . This contact-finger is 80 shifted to right or left and makes contact to right or left (shortly to be described), as the track-switch is to be shifted to right or left.

The letter d^4 denotes a standard of conducting material supported upon and projecting upward from the trolley line-wire e . It carries and supports the non-conducting 85 base-plate e' .

The letter e^2 denotes a left-hand electric switch and the letter e^3 denotes a right-hand 90 electric switch (speaking now with reference to the direction in which the car is advanc-

ing) borne upon said base-plate e' . The latter is represented as out of contact and the former as in contact.

The letter e^4 denotes the intermediate lever by which the switch e^2 is thus put into contact. It bears on its sides pivot-pins f hung in duplicate parti-circular slots f' cut in duplicate plates f^2 depending from base-plate e' for that purpose. The upper end of lever e^4 is connected to switch e^3 through the medium of spring f^3 ; and it results from this arrangement of parts just described that when the finger d^3 is thrown to the position shown in Fig. 2 and is advancing in the direction indicated by the appurtenant arrow such finger strikes the lever e^4 and puts switch e^3 into contact with the line-wire; but if the contact-finger d^3 strikes the lever e^4 when moving in the opposite direction it trips harmlessly by it, producing no substantial effect. It is a matter of course that the other side of the line-wire is provided with a contact device the duplicate of that just described.

The letters g and g' denote respectively the 25 conducting-wires, which respectively conduct the current during contact from the line-wire to the motor underneath, or appurtenant to the track soon to be described. They are insulated and united together into cable 30 g^2 , which runs to a supporting-post g^5 , down the supporting-post into the ground and to the motor, as shown in Fig. 1. This motor is located preferably immediately under the track-switch tongue g^3 , the shifting of which to right or left correspondingly switches the car.

The letter h denotes two field-magnets in the motor. When the motor is operated they receive the current after and in series with the rotating armature h' . When the current comes down from the right it runs through the armature in one direction and when it comes down from the left it runs through the armature in the other direction. Each impulse, therefore, rotates the armature a half-turn always in the same direction. When the armature thus takes a half-rotation, it, through the medium of the crank-pin h^2 on the disk h^3 , (fast on the armature-shaft,) shifts 45 the lever h^4 and this, through the medium of suitable connections, as shown, correspondingly shifts the track-switch tongue g^3 .

Speaking now with reference to the direc-

tion in which the car is advancing, i is the right-hand electric switch which receives the 55 current coming down at the right, and i' denotes the left-hand switch. In the drawings the switches are represented as with the right-hand switch in contact and the motor can only now be operated by a right-hand current. When the left-hand switch i' is in contact the motor can only be operated by a left-hand current; and this is a condition of affairs which is practically necessary in the use of this entire mechanism. 60 65

I claim as my improvement—

1. In combination, the track-switch tongue g^3 mechanically connected by suitable intermediates to lever h^4 adapted to be reciprocated by the partial rotation of armature h' , 70 the field-magnets h electrically connected respectively through electric switches i i' and suitable conductors with overhead electric switches e^2 e^3 , the lever e^4 , and the shifting contact-fingers d^3 carried on the trolley-pole 75 and mechanically connected through suitable intermediates with the operating-lever l , all substantially as described and for the purposes set forth.

2. In combination, the reversible trolley-pole d^2 , the shafts d d' carried thereon, the pinion c^4 , the gear-sector c connected to crank-arm c^2 and crank-pin c^3 , and the slotted crank-arm b^4 carried on shaft b^3 , all substantially as described and for the purposes 85 set forth. 80

3. In combination, the trolley-pole d^2 , shaft d' carried thereon and carrying shifting contact-finger d^3 , conducting-standard d^4 borne on the line-wire, non-conducting base e' , electric switches e^2 e^3 , levers e^4 hung in parti-circular slots f' , springs f^3 , and conductors g g' leading to the motor which operates the switch-tongue, all substantially as described and for the purposes set forth. 90 95

4. In combination, the rotating armature h' , the field-magnets h in series with the armature, the conductors g g' , the electric switches i i' , the crank-pin h^2 adapted to rotate with the armature and the lever h^4 , all substantially as described and for the purposes set forth. 100
